(57) **CLAIM**

The ornamental design for a paint applicator, as shown and described.

DESCRIPTION

FIG. 1 is a front perspective view of my design;
FIG. 2 is a front view of the design;
FIG. 3 is a rear view of the design;
FIG. 4 is a left-side view of the design;
FIG. 5 is a right-side view of the design;
FIG. 6 is a top view of the design;
FIG. 7 is a bottom view of the design;
FIG. 8 is an exploded view of the design shown in FIG. 1;
FIG. 9 is a front perspective view of an alternate position of the design shown in FIG. 1;
FIG. 10 is a front perspective view of a second embodiment of my design;
FIG. 11 is a front view of the second embodiment;
FIG. 12 is a rear view of the second embodiment;
FIG. 13 is a left-side view of the second embodiment;
FIG. 14 is a right-side view of the second embodiment;
FIG. 15 is a top view of the second embodiment;
FIG. 16 is a bottom view of the second embodiment;
FIG. 17 is an exploded view of the design shown in FIG. 10; and,
FIG. 18 is a front perspective view of an alternate position of the design shown in FIG. 10.
In the drawings, the stippling indicates a contrast in appearance. The broken lines are for the purpose of showing the relationship and order of parts of the paint applicator and form no part of the claimed design.
